UNITED STATES PATENT OFFICE.

CHARLES B. SMITH, OF FITCHBURG, MASSACHUSETTS.

DESIGN FOR A FABRIC.

SPECIFICATION forming part of Design No. 17,178, dated March 8, 1887.

Application filed January 5, 1887. Serial No. 223,502. Term of patent 3½ years.

To all whom it may concern:

Be it known that I, CHARLES B. SMITH, a citizen of the United States, residing at Fitchburg, in the county of Worcester and State of Massachusetts, have invented and produced a new and original Design for Fabrics, of which the following is a specification.

The nature of my design is fully represented in the accompanying photograph, to which reference is made.

The design consists of the ground stripes *a*, showing oblique ribs *a'*, and the bird's-eye stripes *b*, on which appear dots *c*. The dots

c are arranged to form zigzag transverse stripes across the stripes *b*, as shown in the accompanying photograph.

I claim--

The design for fabrics herein shown and described, the same consisting of the stripes *a*, showing diagonal ribs *a'*, and the bird's-eye stripes *b*, showing dots arranged in zigzag order across the stripes *b*.

CHARLES B. SMITH.
